(57) **CLAIM**

The new ornamental design for a button cover, as shown and described.

DESCRIPTION

FIG. 1 is a front view of the button cover.

FIG. 2 is a top side view of the button cover.

FIG. 3 is a bottom side view of the button cover.

FIG. 4 is a right side view of the button cover.

FIG. 5 is a left side view of the button cover.

FIG. 6 is a front perspective view of the button cover shown in the environment of a ribbon about a vase, wherein said ribbon has a button integrated therein.

FIG. 7 is a front perspective view of the button cover shown in the environment of a sticker on a vase, wherein said sticker has a button integrated therein

FIG. 8 is a front perspective view of the button cover shown in the environment of a pick within a vase, wherein said pick has a button integrated therein; and,

FIG. 9 is a front perspective of the button cover shown in the environment of a charm hanging from a vase, wherein said charm has a button integrated therein.

The broken line showing of parts of the drawings is included for the purpose of illustrating use and environment and forms no part of the claimed design.

1 Claim, 5 Drawing Sheets
